US00D827360S

(12) **United States Design Patent** (10) Patent No.: **US D827,360 S**
(45) Date of Patent: ** Sep. 4, 2018

(54) **RICE COOKER**

(71) Applicant: **KONINKLIJKE PHILIPS N.V.**,
Eindhoven (NL)

(72) Inventors: **Waikit Chung**, Shanghai (CN); **Deguo Miao**, Shanghai (CN)

(73) Assignee: **KONINKLIJKE PHILIPS N.V.**,
Eindhoven (NL)

(**) Term: **15 Years**

(21) Appl. No.: **35/502,244**

(22) Filed: **Jul. 4, 2016**

(80) **Hague Agreement Data**

Int. Filing Date: **Jul. 4, 2016**

Int. Reg. No.: **DM/091719**

Int. Reg. Date: **Jul. 4, 2016**

Int. Reg. Pub. Date: **Jan. 6, 2017**

(51) LOC (11) Cl. 07-02

(52) U.S. Cl.

USPC **D7/354**
